UNITED STATES PATENT OFFICE.

FREDERICK MITCHELL, OF YONKERS, NEW YORK.

SIGN.

SPECIFICATION forming part of Letters Patent No. 412,972, dated October 15, 1889.

Application filed January 8, 1889. Serial No. 295,728. (No model.)

To all whom it may concern:

Be it known that I, FREDERICK MITCHELL, of Yonkers, in the county of Westchester and State of New York, have invented a new and useful Improvement in Signs, of which the following is a full, clear, and exact description.

My invention relates to an improvement in signs, and has for its object to provide a simple, convenient, and expeditious manner of constructing a sign, whereby letters may be rapidly placed upon a suitable background to construct words and sentences, and can also be quickly removed or shifted, and also wherein the letters forming the words or sentences may be placed in lines running horizontally or diagonally of the background or in curves, as may be desired.

To that end the invention consists in the novel construction and combination of the several parts, as will be hereinafter fully set forth, and pointed out in the claims.

Reference is to be had to the accompanying drawings, forming a part of this specification, in which similar figures of reference indicate corresponding parts in all the views.

Figure 1 is a front elevation of a portion of a sign. Fig. 2 is a vertical section on line xx of Fig. 1. Fig. 3 is a perspective view of one of the letters detached from the sign-plate.

The prime object of the invention is to provide a background to constitute the body of the sign, upon which any word may be rapidly constructed, and the letters throughout may be changed into other words, as may be desired.

To that end the body 10 of the design consists of a perforated plate, which plate is preferably mounted in a suitable frame 11. The plate is ordinarily constructed of metal, but may be of any other desired material. It is made in the same manner as the well-known perforated plate of commerce. The perforations 12 in the plate may be arranged in any desired manner and may be made to cover the entire plate or only a portion of the same. The perforations employed are ordinarily circular, as illustrated in Fig. 1; but they may be diamond-shaped, as shown in Fig. 3, or may be of any desired contour. In practice the perforations upon each plate are preferably of the same shape.

The letters 13 may be constructed of any suitable material—such as metal, wood, glass, ivory, rubber, &c.—and may be of any form, 55 with plain or with ornamental surfaces. When the circular form of perforation is employed, each letter is provided with one or more (preferably two) studs 14, which studs are projected from the rear face of the letter, 60 and may be either attached thereto or formed integrally therewith. The upper stud is curved upward, thus forming a hook, so that in applying a letter 13 to the plate 10 the said letter must be held at an acute angle to the 65 latter, in order to permit insertion of such hook, and then lowered or brought down to the vertical position, (shown in full lines,) when the free end of the hook will enter the perforation next above that in which its body 70 rests. The letter is thus held suspended by the hook; but it is advisable to upset the end of the lower stud, in order to hold the lower end of the letter firmly against the plate 10. It will be understood that the letters, as aforesaid, may 75 be placed diagonally of the perforated plate, or in curved lines, or horizontally, as the fancy of the operator may dictate. The upper stud is bent upon itself to assume a curved or a diagonal line, (preferably the former,) and when 80 the letter is to be placed in position on the body-plate the hook thus formed, which is also illustrated in Fig. 2, is first introduced into the perforation, the letter being held at an angle to the plate, and then the letter is 85 brought to a perpendicular position parallel to and in contact with the plate, whereupon the lower stud will, as the letter swings downward, enter one of the perforations.

Any number of studs may be employed in 90 connection with the letters, and the said studs may be distributed in a manner to best sustain the several letters. When it is desired that the perforated background should be curved, the letters may be made to conform 95 thereto.

In conjunction with the letters, numerals and punctuation-marks may be similarly constructed and such bas-relief or outline objects as would be used in their decoration.

Having thus described my invention, what I claim as new, and desire to secure by Letters Patent, is—

1. The combination, with the sign-plate

having a series of perforations one above another, of a letter having a fixed curved stud or prong on its back, which is adapted to pass freely through said perforations, as shown 5 and described, whereby said letter may be attached and held suspended against the face of the plate, and also detached, as specified.

2. As an article of manufacture, a letter having a fixed curved prong on its back, as and for the purpose specified.

FREDERICK MITCHELL.
